UNITED STATES PATENT OFFICE.

QUIMBY S. BACKUS, OF BRANDON, VERMONT.

WATER-HEATER.

SPECIFICATION forming part of Letters Patent No. 787,656, dated April 18, 1905.

Application filed December 13, 1904. Serial No. 236,708.

To all whom it may concern:

Be it known that I, QUIMBY S. BACKUS, a citizen of the United States, residing at Brandon, in the county of Rutland and State of Vermont, have invented certain new and useful Improvements in Water-Heaters; and I do hereby declare the following to be a full, clear, and exact description of the invention, such as will enable others skilled in the art to which it appertains to make and use the same.

My present invention relates to the class of gas-heaters for heating water brought to the heater from any source of supply through a supply-pipe; and it consists in certain improved constructions and combination of parts whereby a cheap and efficient heater is produced.

In the drawings I have shown a water-heater embodying my invention, and said invention is disclosed in the following description and claims.

In the drawings, Figure 1 is a view of my improved heater in elevation, and Fig. 2 is a vertical section of the same.

In said drawings, A is the inclosing casing for said heater, which is provided with a lining of asbestos *a* to prevent radiation of heat. The heating of the water is effected in a coil of pipe B within said casing. This coil is a continuous coil having its two ends adjacent to the bottom of the structure, to one end of which is attached the supply-pipe *b*, and the other end is connected to the discharge-faucet *b'* on the outside of the casing. The end coils of this heater are brought in close proximity to each other and the coils above come together and intersect and overlap each other, as shown in the drawings. The burner C is placed in the bottom of the casing and extends laterally, so as to bring the outer sides beneath the ends of the coil. This burner is preferably constructed of a pyramidal or like form and is provided at its upper part with centrally-disposed flame-openings *c*, giving vertical flames, and below this it is provided at its sides with one or more rows of flame-

openings *c'*, directing their flames within the coils and against the portion of the pipes of the coils nearest the burner. The flames from the upper orifices will be directed toward or 50 against the interlapped and other coils above the burner. This burner is preferably an injector-burner or one designed to burn such an admixture of air and gas as to insure complete combustion.

C' is the gas-supply pipe, and *c* the cock controlling the same.

This construction gives a large heating-surface and so distributes the same as to utilize the greatest amount of heat produced by the 60 burner.

By making the heating-coil in the form shown I am enabled, by changing the length of the coil and the size of the burner, to construct heaters of varying capacity from the 65 same materials.

What I claim, and desire to secure by Letters Patent, is—

1. In a water-heater, the combination with the casing of a burner and heating-coil within 70 said casing, said heating-coil being composed of a continuous pipe and including nearly vertically-disposed spiral coils at the incoming and outgoing ends of the heating-coil, said end coils being in close proximity to the 75 burner, with their upper ends over the burner, substantially as described.

2. In a water-heater, the combination with an inclosing casing of a burner and heating-coil within the said casing, said heating-coil 80 being composed of a single continuous pipe formed into a spiral coil, the ends of which are disposed in a nearly vertical position in close proximity to the burner with intervening positions directly above the burner, substantially as described.

In testimony whereof I affix my signature in the presence of two witnesses.

Q. S. BACKUS.
